UNITED STATES PATENT OFFICE.

EDWARD C. MORRIS AND LOUIS J. HALL, OF CHICAGO, ILLINOIS; SAID HALL ASSIGNOR TO SAID MORRIS.

MACHINE FOR STAMPING AND SEALING MAIL-MATTER.

No. 884,838.

Specification of Letters Patent.

Patented April 14, 1908.

Application filed October 2, 1897, Serial No. 653,832. Renewed June 8, 1900. Serial No. 19,626.

To all whom it may concern:

Be it known that we, EDWARD C. MORRIS and LOUIS J. HALL, of Chicago, in the county of Cook and State of Illinois, have invented 5 certain new and useful Improvements in Machines for Stamping and Sealing Mail-Matter, of which the following is a specification.

This invention relates to improvements in machines for stamping and sealing mail matter, such as envelopes, cards and the like, and in the present instance the invention is embodied in a machine more particularly designed for use in stamping and sealing envelopes, although it will be understood that the 15 essential features of the improvement may be applied in machines for stamping circulars and even newspapers, if desired.

The object of the invention is to provide an apparatus of the character referred to which 20 will render possible the sealing and stamping of any considerable quantity of mail matter with greater expedition and economy of operation than by hand labor or any other means or methods heretofore employed for 25 the purpose.

The invention further contemplates the handling of postage stamps in the original form in which they are supplied by the Government, *i. e.*, in sheets of one hundred stamps 30 each, although capable of handling equally well continuous sheets of stamps, in case they can be obtained in the latter form.

In a machine embodying our invention as applied to the stamping of envelopes, the latter are placed in quantities upon or within a suitable table or support along which they are moved until brought in succession within the range of suitable carrier mechanism by which they are brought into position to receive the stamp. The sheets of stamps are mounted within a carriage by which the successive stamps of each row in the sheet are presented in turn to the action of an affixing mechanism by which the stamp is severed 40 and affixed to the envelop that is at that moment presented by the carrier mechanism. The transverse movement of the carriage will be a step by step movement which at the end of each row of stamps will be interrupted by 45 one interval while the succeeding row is fed into position opposite the plunger, and the end stamp of the row is severed and applied by the latter. The step by step movement then proceeds in the reverse direction until 50 that row is exhausted whereupon a third row

is fed forward, and this operation is repeated as long as the machine continues to run.

For the handling of successive sheets of stamps the improvement involves the provision of any suitable means for supplying 60 succeeding sheets of stamps to be in turn advanced row by row to the affixing mechanism as each preceding sheet is exhausted. One such suitable means is herein disclosed in the form of a double web of flexible material, 65 or fabric, between which the sheets of stamps are placed with their marginal edges closely adjoining each other. This double web, with its inclosed stamps is provided on a roll within the carriage and unwound gradually 70 as the stamps are needed, the fabrics or webs being separated as they are unwound to release the inclosed stamps which are thus produced in a practically continuous sheet of 75 which the actually separate parts are in such exact succession that no gap appears between them. If found necessary the separate sheets may furthermore be connected by narrow adhesive strips which would positively prevent their separation. The separate 80 webs as they are unwound to release the stamps will be conveniently wound up again on rolls provided for the purpose and these rolls will also conveniently constitute the stamp feed rolls of the carriage and may be 85 used as such to feed forward a single or continuous sheet of stamps even if the webs are omitted. Conveniently also the three rolls thus provided for the webs will be made capable of being reversely operated so as to replace 90 the double web on the first roll, and will thus afford a means of introducing a new series of sheets of stamps between the fabrics after the first lot of stamps has been exhausted. 95

The stamping mechanism thus generally described may obviously be employed without reference to the provision for sealing the envelopes, but the complete invention further contemplates the employment of means for 100 this purpose in connection with said stamping mechanism so that both operations may be carried on by the same machine and simultaneously. To this end moistening devices are provided in the path of the envelopes as 105 they are moved in succession from the original pile and the envelop flaps are brought into contact with said moistening devices by the action of the carrier mechanism. After being thus moistened the flaps are turned 110

down by suitable pressure devices which are brought to bear by the continued movement of the envelop so that the latter is sealed thereby. In the present instance such sealing devices are provided between the plunger and receiving table. The adhesion of the stamps is also in this instance caused by moistening the envelop in its passage from the receiving table to the plunger and separate moistening devices are conveniently provided for this purpose. Obviously however, an operative mechanism involving a generally similar construction, so far as the application of the stamps is concerned, might be provided in which the stamps themselves instead of the envelop were moistened before being applied.

The invention will be more fully understood from the following description of one construction of machine practically embodying it, when taken in connection with the accompanying drawings illustrative thereof and in which:—

Figure 1 is a plan view of an envelop sealing and stamping machine of the class referred to. Fig. 2 is front elevation thereof. Fig. 3 is an end elevation. Fig. 4 is a sectional side elevation taken on line 4—4 of Fig. 1. Fig. 5 is a perspective detail showing the mounting of the idle roll of the carrier mechanism. Fig. 6 is a sectional detail thereof. Fig. 7 is a fragmentary perspective view showing the manner of arranging the envelops on the receiving table and the method of moistening the flaps. Fig. 8 is a rear view of the plunger mechanism. Fig. 9 is a fragmentary side view thereof. Fig. 10 is a top plan view of the device for moistening the faces of the envelops. Fig. 11 is a front elevation of the swinging moistening plate removed. Fig. 12 is an end elevation thereof.

In said drawings A designates the base or supporting frame of the machine at the front of which the main driving shaft B is journaled in suitable bearings b. Said shaft is rotated from any suitable motor or foot power mechanism by means of a belt or other driving connection b¹ passing over a pulley b² on the shaft. As herein shown the pulley b² is provided with an integral flange b³ and rotates freely upon the shaft, the face of said flange being provided with clutch teeth b⁴ adapted to interlock with corresponding teeth b⁵ on the face of a sliding clutch collar b⁶ which may be thrown into or out of engagement with the flange b³ by any suitable shifting handle b⁷. The clutch collar b⁶ slides on a feather on the shaft B so that when the clutch is in engagement with the pulley the shaft is rotated whereas when out of engagement the pulley rotates freely while the shaft remains stationary. The shaft itself operates the plunger mechanism and stamp carriage, as hereinafter more

fully described, while the driving pulley b² is operatively connected with and actuates the carrier mechanism by means of the following constructions: B¹ designates a bevel gear rigidly secured to an internal sleeve b⁸ which also is rigidly attached to the pulley b² so that the gear and pulley rotate together. Between the gear and pulley said sleeve passes through and is supported by a bearing b⁹ from the frame A and the end of the shaft B passes loosely through the sleeve b⁸ which serves as an end journal for the shaft. The gear B¹ intermeshes with a second bevel gear C which is secured to the end of a short shaft c that is mounted at right angles to the shaft B in bearings c¹ on the base A. At its inner or rear end, the shaft c carries a rigidly attached crank disk or arm C¹ from the face of which a crank or wrist pin c² projects rearwardly into a vertical slot d in the face of a carrier plate D so arranged that as the wrist pin revolves about the shaft c the carrier plate is given a horizontal reciprocatory movement. At its lower end the plate D is shown as supported upon a horizontal guide rod d¹ upon which it is free to slide, said guide rod being mounted in supporting lugs d² on the base A. At its upper end said plate D is secured to a sliding bar D¹ so as to reciprocate with the same. The bar D¹ is loosely mounted in supporting brackets d³ and d⁴ rising from the base A and is made sufficiently longer than the distance between said brackets to admit of its being moved back and forth the full throw of the crank C¹ without slipping from its bearings in said brackets. The principal function of the bar D¹ is to carry a number of presser arms D², D³, and D⁴ which are rigidly but adjustably fastened upon the bar by means of set screws d⁵ or equivalent clamping devices. Between the presser arm D³ and D⁴ said bar passes loosely through the lugs d⁶ of the plate D and the ends of the lugs d⁶ are shown as abutting closely upon the adjacent ends of the presser arms. The bar D¹ is therefore free to oscillate independently of the plate D while held against endwise movement with reference thereto. This oscillatory movement of the bar is designed to throw the upper ends of the presser arms forward against the envelop at the beginning of each working stroke and away from the envelop at the end of the working stroke and during the return stroke. Any suitable mechanism may be employed to this end, and in this instance we have shown a toggle D⁵ inserted between the presser arm D⁴ and a lug d⁷ which projects out from the carrier plate D. Said toggle comprises a short link d⁸ pivoted at d⁹ to the lug d⁷ at one of its ends and pivoted at its other end by a pin d¹⁰ to the end of a similar short length d¹¹ which in turn is pivoted at its other end at d¹² to the back of the presser arm D⁴. To operate the

toggle a tripping bar D^6 is also secured to the center pin d^{10} and is arranged to slide through an aperture in the upper end d^{13} of the bracket d^3 which is projected upward for this purpose. Suitable stops d^{14} and d^{15} are provided on the tripping bar at a distance apart somewhat less than the stroke of the carrier and are so arranged that at the outer end of said stroke the stop d^{14} strikes the bracket d^{13} and operates the toggle to force the presser arm D^4 out against the envelop, while at the inner end of the stroke the stop d^{15} strikes the bracket d^{13} and operates the toggle to withdraw the presser arm from the envelop. As herein shown the inner end of the tripping bar D^6 is made in the form of a separate head D' which is flattened at d^{16} to pass between the links d^8 and d^{11} and engage the pivot d^{10} , and to which the outer portion D^6 is secured by an adjustable screw joint. The stop d^{14} is in this instance a check nut by which the screw joint is locked in any desired adjustment, and a further adjustment is provided by making the stop d^{15} screw upon the end of the tripping rod and securing it in place by a check nut d^{17} . Inasmuch as all the presser arms are rigidly secured to the bar D^1 the oscillatory movement thus given to the presser arm D^4 by the toggle will be transmitted equally to the other two.

E designates a receiving table upon which the envelops are originally placed in a pack of any desired number with each envelop arranged in a vertical position and resting upon its lower edge or that opposite the sealing flap. The forward end of the table E terminates at a point adjacent to the outer presser arm D^4 at the outer end of the throw of the latter. An end wall or plate E^1 guards the front end of the table and is cut out, as shown at e in Fig. 1, to permit free movement of the arm D^4 . The pack of envelops is continually forced against this guard wall by a movable plate or piston E^2 which is pressed forward by any suitable mechanism, consisting in this instance of cords e^1 passing over suitable sheaves e^2 and having weights e^3 secured to their ends. Said cords are attached to brackets e^4 and are secured to the plate E^2 and extend through slots in the side walls E^3 of the table. The face of the presser arms will be desirably provided with a surface block d^{18} of rubber or other material the friction of which against the end envelop will be greater than the friction of the envelops against each other. Consequently when the presser arm D^4 is forced against the pile of envelops through the aperture e in the wall E^1 , and is then moved horizontally by the crank C^1 it will slide the front envelop of the pack along with it away from the remaining envelops and toward the plunger mechanism. The rest of the envelops will be prevented from moving endwise at this time by the inner side wall E^3 of the table, which wall

will extend forward within a short distance of the front wall E^1 so as to leave but a narrow space e^6 through which the envelop which is engaged by the presser arm must pass. A light spring e^7 is furthermore herein shown as provided at this point to yieldingly permit the passage of said first envelop whether it be thicker or thinner, while holding back the second and succeeding envelop for the time being. As the envelop is thus carried inward from the table E it passes between the presser arm and two series or sets of idle rolls F, F' , which simply operate as guide rolls to determine the path of the envelop and resist the pressure of said presser arm. These rolls are desirably spring supported so as to press yieldingly against the envelop and are herein shown as arranged in two sets and mounted upon a suitable carrying stand f which is conveniently bolted to the base A . The first set of rolls F consists in this instance of three rolls journaled on pins f^1 which rise from a common connecting bar f^2 , said pins being inserted in upwardly projecting lugs f^3 of said arm. The bar f^2 is provided at its opposite ends with lugs f^4 through which horizontal pins f^5 extend forwardly into similar lugs f^6 of the stand f . These pins f^5 slide loosely through the apertures in the lugs f^6 and thus support the bar in such manner as to permit a horizontal backward and forward movement. A plate spring f^7 is herein shown as inserted between an upwardly projecting lug f^8 on the rear edge of the stand f and two downwardly projecting lugs f^9 on the front edge of the bar f^2 near the ends thereof. This spring will obviously tend to force the rolls F forward against the presser arm while permitting the rolls to yield a greater or less distance as envelops of varying thicknesses are forced through by the presser arm. The other set of rolls F' is supported in an identical manner and differs only in containing four rolls, as herein shown, instead of three.

The means provided in this instance for moistening the gum on the sealing flaps of the envelops comprises a small water receptacle or tank G provided immediately in front of the front wall E^1 of the receiving table and just above the path of the presser arm. The envelops X will be arranged with their flaps opened out horizontally and overlapping each other, the first envelop of the pack being placed with its flap projecting over the outer end of the tank G and the succeeding envelops having their overlapping flaps pointed forwardly in the same manner. A wire deflector G^1 is shown as projecting from the front wall of the tank rearwardly and downwardly into the tank and is so arranged that as each envelop is moved inward its flap will be forced downward by the wire into the water with which the tank will be filled. The moistened flap will then be

closed down against the body of the envelop by a sealing bar H which in this instance consists of a bent wire secured at one end by solder or otherwise to the wall of the tank G 5 and at its other to the end of a laterally projecting plate i carried by the plunger supporting standard I. The operative portions of this sealing wire consist of a downwardly rearwardly and inwardly extending portion h which gradually turns the flap down against the body of the envelop from the horizontal position in which it emerges from the tank G, and a continuing vertically upturned portion h¹ which is intended to exert a pressure 10 across the entire extent of the flap tending to secure its adhesion. The open space on the front side of the path of the envelop between the inner end e⁸ of the front wall of the receiving table and the outer end of the plate 15 i is provided at this point to permit the envelop flap to be closed down in the manner stated. Beyond this point the envelop is closely confined in its path of movement up to the time it is ejected into the receiving 20 box after all operations are completed. 25

The devices provided in this instance for moistening the face of the envelop preparatory to the application of the stamp thereto comprise a swinging arm J mounted on a vertical pivot j at the upper end of a vertically projecting lug f¹⁰ of the standard f which supports the rolls F, F¹. The face of the arm J is covered with a brush or felt or other absorbent surface J¹ capable of holding a considerable amount of moisture. The arm J is pressed forward by a spring J² which is secured at its lower end to a lug f¹¹ of the bar f² and at its upper end engages the rear side of a downwardly projecting lug j¹ of the swinging arm. The end of the moistening brush or felt is thus maintained in close proximity to the adjacent face of the laterally projecting plate i on the front side of the envelop passage, so that as each envelop is forced through it will be moistened wherever the brush or felt strikes it.

It being undesirable and unnecessary to moisten the face of the envelop anywhere else than at the point of application of a stamp, means are provided for forcing back the swinging arm as soon as the front end of the envelop has passed by a sufficient distance. Such means consist, as herein shown, of a curved finger j² secured to the end of the arm J and thence bent upwardly, forwardly, and downwardly over and in front of the plate i. A cam surface or plate j³ secured to the middle presser arm D³ is arranged to strike the lower end of the finger j² 50 in the forward movement of the carrier and forces the moistener back away from the envelop at the predetermined moment, allowing it to return again to moisten the next envelop after the first envelop has passed. To 55 supply moisture to the brush or felt a small

pipe j⁴ terminating in the funnel j⁵ is provided at the outer end of the arm J. Water may be dripped into this funnel from any suitable tank or supply, not herein illustrated, and suitable provision will also be made for carrying off any excess of moisture from the brush or felt if found necessary.

The mechanism herein shown for applying or affixing the stamps to the envelops is constructed as follows: I designates a standard secured to the base plate and in this instance made with an upper detachable section I¹ which, however, may be made integral. At the top of the standard a plunger arm K is mounted to reciprocate horizontally from front to rear and is herein shown as sliding between ways i¹ of the standard, said ways being in this instance made adjustable by means of screws i². Said plunger arm projects rearwardly over the path of the envelops and thence downwardly to a point opposite a rectangular die plate L. This die plate is arranged behind the path of the envelop and is herein shown as supported at the upper end of a standard L¹ which is also secured to the base A. The die plate L will conveniently be made of suitable tool steel and of such shape as to be readily secured within a suitable aperture in the upper end of the standard L¹. The rectangular opening of the die plate will be of the exact size and shape of the postage stamp label or the like for which the machine is intended and if stamps of different sizes or shapes are to be applied several die plates will be provided accordingly. The plunger proper K¹ projects forwardly from the depending rear end of the plunger arm. Said plunger is made of the exact size of the die plate and is designed to be carried entirely through the die plate and against the opposite side of the envelop passage each time the plunger arm is reciprocated. The sheet of stamps will be guided to a position at the rear of the die plate and between it and the plunger by means of sheet metal guides l l¹ and the arrangement for feeding in the stamps will be such, as hereinafter described, that an end stamp of the uppermost row of stamps will be passed before the opening in the die plate just previous to the movement of the plunger so that said movement will sever this stamp from the rest of the sheet and force it forward against the moistened surface of the passing envelop, the mucilage side of the stamp being faced forward so that it will adhere. Under ordinary circumstances it will be evident that each stamp will be severed only along two of its edges, i. e., a side edge and its bottom edge, so that the cutting operation will not be difficult. Preferably, however, the cutting edges of either the die plate or plunger will be arranged at a sufficient angle to afford a shearing cut, as shown in this instance in the oblique edge l² of the die, which will fur- 130

ther facilitate the cutting operation. Means are also provided for clamping the remaining portion of the sheet of stamps against movement while the end stamp is being severed. 5 and applied, consisting in this instance of a spring pressed arm K^2 herein shown as supported on a sliding pin k mounted in a lug k^1 on the upper side of the plunger arm K . Said clamping arm K^2 is bifurcated to depend on either side of the plunger arm K and terminates in clamping ends k^2 located at each side of the plunger K^1 .

The front end of the pin k is enlarged or headed, as shown, and between this head and 15 the lug k^1 of the plunger arm the coil spring k^3 is in this instance inserted to exert a yielding pressure on the clamping arm tending to maintain the same at the inner limit of its movement relatively to the plunger. When 20 the latter is forced forward to sever and to affix the stamp the ends k^2 of the clamping arm on the side from which the stamp carriage is approaching will be carried against that stamp which stands laterally adjacent 25 to the one which is being severed. Then as the plunger continues its forward movement the spring k^3 will yield and the clamping arm will remain stationary but firmly pressed against the adjacent surface of the die plate 30 or its support with the stamp intervening. This clamping of the stamp adjacent to the one which is being severed will occur just before the plunger enters the die, by reason of the fact that the front surface of the clamping 35 ends k^2 normally projects slightly in front of the plane of the plunger face so that they will strike the stamp before the plunger does, and the obvious result of the clamping action is to prevent any tendency of the other 40 stamps being mutilated or displaced by being drawn partially into the die with the stamp which is severed. The opposing surface of the envelop passage which receives the impact of the plunger is desirably made yielding 45 so as to insure a pressure sufficient to affix the stamp without danger of injuring the parts, and to this end is herein shown as comprising a yielding plate i^2 which is given a sliding support by pins i^3 and i^4 which pass 50 freely through suitable holes in the upper portion of the standard I . A plate spring i^5 is shown as inserted between the yielding plate i^2 and the supporting standard to normally force the former forward, its movement 55 in this direction being shown as limited by the heads of the lower pins i^4 which act as stops. When the plunger strikes the envelop the spring i^5 will yield sufficiently to permit the plate i^2 to slide back a greater or 60 less distance as necessitated by the thickness of the envelop which is being stamped.

Suitable devices are provided for reciprocating the plunger mechanism thus described at correct intervals, and are in this 65 instance constructed of follows: M design-

nates a rocker arm pivoted between its ends at m to the front of the standard I . The upper end m^1 of the rocker arm is connected with the front end of the plunger arm K in such manner that any movement of the 70 rocker arm must reciprocate the plunger. As herein shown such connection is made by passing a headed bolt k^4 through a loosely fitting aperture in the end of the rocker arm into the end of the plunger arm. A lock nut 75 k^5 is shown as inserted between the extremity of the rocker arm and the end surface of the plunger arm and enables the bolt to be locked in an adjusted position, such as to provide just space enough between the head of the 80 bolt and the lock nut to allow the rocker arm necessary play without lost motion. Said rocker arm is herein shown as receiving an oscillatory movement from the main shaft B , and to this end the latter carries a double arm 85 B^2 having projecting pins b^{10} which are desirably made to carry friction rollers b^{11} that are adapted to strike the lower end of the rocker arm in each revolution of the shaft. This accomplishes the working stroke of the 90 plunger and the action in this particular is positive, so that the plunger will necessarily be forced inward to affix a stamp at exact intervals occurring twice in each revolution of the main shaft. A slight dwell of the 95 plunger at the moment the stamp is applied may be conveniently attained with this construction by forming the front of the rocker arm with a slight inward curve, as shown at m^2 , at the point where the striking pins b^{10} 100 pass their dead center relatively to the rocker arm. The return movement of the rocker arm and plunger is in this instance effected by a spring pressed pin M^1 that is seated in a suitable socket i^6 of the standard I and is 105 normally forced forward against the rocker arm by a suitable coil or other spring placed behind it. To enable the return of the plunger to be accomplished very quickly by such spring action a sharp inward bend is 110 given to the rocker arm at a point m^3 just above the dwell curve m^2 , so that immediately after the period of dwell the striking pins will pass almost instantly out of contact with said rocker arm. 115

After the stamp has been applied by the affixing mechanism the envelop is passed on between fixing rolls N and O which will apply further pressure to the entire envelop and thus insure the adhesion of the stamp and the sealing of the flap. On passing from these rolls the envelop is ready to be moved from the machine and, as herein shown, is dropped into a chute P through which it falls into any suitable receptacle P^1 . Said fixing rolls N and O will be conveniently held in yielding contact by any suitable spring support which, for example, may be applied to the roll N in the same manner substantially as heretofore illustrated in connection with 120 125 130

the rolls F, F¹, but which is not specifically herein shown. The roll O is herein shown as actuated from a pulley B³ on the main shaft by means of a belt b¹² which passes over 5 an adjustable idler O¹ and around the belt pulley o on the supporting shaft o¹ of said roll, the diameters of the pulleys being made such as to accomplish the surface speed of 10 the fixing rolls sufficient to withdraw and reject the envelopes as rapidly as may be found necessary. A yielding spring N¹ provided in the envelop passage adjacent to the fixing rolls aids in guiding the envelopes properly 15 between them. The bottom of the envelop passage formed by the standards f and L¹ will be made smooth and substantially continuous throughout its length, so as to secure an easy sliding movement of the envelopes thereon.

20 The stamp carriage and accompanying mechanism for properly supplying the stamp successively to the action of the affixing mechanism are in this instance constructed as follows: Q designates a carriage frame of generally rectangular shape, mounted to slide back and forth transversely of the machine, i. e., parallel with the main shaft of the carrier mechanism. The sliding support for the carriage is herein shown as comprising 25 parallel bars or rods R supported in brackets r from the base A and serving as tracks for friction rolls q journaled to the carriage. Means are provided for reciprocating the carriage by a step by step movement effected, in the approved construction shown, by 30 an endless reversing screw S provided in the surface of a suitable cylinder S¹, the shaft of which is arranged parallel with the path of movement of the carriage and supported 35 within bearings s of the base A. Rotary movement is given to this cylinder and screw intermittently and between each working 40 stroke of the plunger. A fixed stud q¹ on the carriage is arranged to project into said screw and the intermittent movement of the latter will, therefore, actuate the carriage in correspondingly intermittent steps. The 45 rotary movement applied to the screw for each plunger movement will be so proportioned with relation to the pitch and diameter of the screw that each of said movements, except at reversing points, will carry the carriage along the exact width of one stamp. At 50 each end of the screw or, in other words, at the meeting points of the two helices which must necessarily characterize this mechanical element, the movement of the carriage will be reversed and the connecting curve of the two helices will be made sufficiently gradual, as shown at s¹, to prevent any jar at such time. The parts will be, 55 moreover, so adjusted that the rotary impulse which accomplishes the reversal will leave the stud q¹ in the same transverse plane, relatively to the axis of the screw, at the end

of said impulse as at the beginning, the stud and carriage moving during this interval to the extreme end of their path and back again to the same position as the stud passes the point of the joining curve s¹. This

70

movement of the carriage, however, will be idle and the practical effect will be the same as though the carriage had remained stationary during this interval. The position of the stud at the beginning of such an interval is shown at q¹ in Fig. 1, and its position in the screw at the end of such interval is indicated by dotted lines at q² in said figure. The object of securing such dwell of the carriage at reversing points is to permit the succeeding row of stamps to be fed forward after the end stamp of the preceding row has been applied and to give opportunity for the plunger to operate on the first stamp of said succeeding row before the effective return movement is started, it being obvious that if said return movement began instantly with the next actuating impulse of the screw S after the action of the plunger on the last stamp, the next movement of the plunger would 85 strike the second stamp of the succeeding row and the first stamp of said row would be missed entirely.

75

The intermittent rotation of the screw S may be accomplished by any suitable connection from the main shaft. As herein shown such connections comprise a ratchet wheel S² fixed upon the projecting end of the screw shaft s² and adapted to be engaged by

90

ratchet dogs s³ mounted in two opposite oscillatory arms S³ and S⁴ which are loosely

100

journaled on the shaft s² between the ratchet wheel S² and the end bearing s of the shaft. Wrist pins s⁴ project from the arms S³ S⁴ and are connected by separate pitmen S⁵ and S⁶ with a common crank B⁴ on the end of the main drive shaft. With this construction two separate impulses of the screw S result

105

with each revolution of the drive shaft. It is obviously necessary that the feed of the carriage to present each succeeding stamp must occur between the time at which the plunger is withdrawn from the die plate and the time at which it enters the die plate again.

110

This necessary suddenness of movement is in this instance accomplished by providing for a considerable lost motion between the rotary movement of the crank arm B⁴ and the oscillatory movement of the ratchet arms S³ S⁴. Such lost motion is pro-

115

vided, as herein shown, by allowing each wrist pin s⁴ to project into a slot s⁵ in the end of its engaging pitman, so that in each reciprocation of the pitman the ratchet will re-

120

main unmoved until the wrist pin has traversed the length of the slot and come in contact with the end thereof. An exact adjustment of the movement with relation to the movement of the other parts is arranged

125

for by providing adjustable stops s⁶ at the end

130

outer ends of the slots s^5 and by making the length of the pitman adjustable, as shown at s^7 .

The mechanism for feeding a new row of stamps forward after the last stamp of the preceding row has been applied is herein shown as comprising a pair of rolls T and U by which the sheet of stamps is carried forward between guides q^3 and q^4 of the carriage 10 and between the guides l and l^1 which direct it to the die plate. The roller T is given an intermittent rotary movement at the reversing points of the carriage movement by means of a shaft T^1 which passes freely 15 through bearing q^5 on the carriage and upon which the roll T slides on a feather. The outer end of the shaft T^1 is revolvably supported in a bearing bracket T^2 rising from the base A, and is provided near said bearing 20 bracket with a ratchet wheel T^3 . Between the ratchet wheel and the bracket a ratchet arm T^4 is mounted to oscillate axially about the shaft T^1 and is herein shown as rigidly secured to a sleeve t which is revolvably 25 mounted in the bearing bracket T^2 around the end of the shaft T^1 . This ratchet arm is arranged to be oscillated once in each revolution of the screw S, by means of a crank arm s^8 which is rigidly secured on the shaft s^2 30 and is provided with a wrist pin s^9 bearing a friction roller s^{10} that is adapted to strike an oscillatory lever T^5 . Said lever is shown as pivoted at t^1 to the base A and at its upper end is slotted to receive a wrist pin t^2 on the 35 ratchet arm T^4 . The return movement of the ratchet is accomplished by a spring t^3 which forces a sliding pin t^4 forwardly against the lever T^5 . The crank arm s^8 is placed on the shaft in such relative angular arrangement that it oscillates the ratchet arm T^4 40 and accomplishes a rotary movement of the roller T sufficient to advance another row of stamps immediately after the action of the plunger upon the last stamp of the preceding 45 roll.

As herein shown the stamps are fed between the rollers T and U from a supply roller V which is journaled at v in brackets q^6 on the carriage frame. If the stamps can 50 be obtained in a continuous or endless sheet they may be rolled up on the supply roller and carried between the rollers T and U without difficulty. For the purpose, however, of providing for the successful handling 55 of stamps which are supplied in short sheets we have shown additional devices as follows: W, and W^1 designate two continuous webs of any suitable material or fabric which are designed to act as a carrier for the several 60 sheets of stamps. The upper web W will be carried from the supply roller to the upper roll U and in practice may conveniently be attached at its ends to the surfaces of the rolls V and U so as to be permanently attached thereto. The lower web W^1 is car-

ried from the supply roller V between the rolls T and U and partially around the former to a fourth roller X. This web may also be conveniently secured to the surface of the roll V at the same point with the upper web 70 W and at its other end may be secured to the surface of the roll X. The two receiving rolls U and X are given a rotary motion at the same surface speed by means of belts T^6 which pass around the extremities of the 75 rolls U and X and are guided partially around the main feed roll T by means of an idler T^7 , the ends of the three rolls being herein shown as slightly reduced to receive said belt. With this construction the sheets of stamps S 80 will be released from the two webs as they separate at the line of contact between the rolls T and U and the stamps will be passed upward through the guides, as before described, while the webs themselves will be 85 wound up separately upon their respective receiving rolls. As herein shown the roll U is maintained in position by having its journals u inserted in open slots Q^1 in the upper ends of bracket arm Q^2 which rise from the 90 carriage Q, and the lower roll X is similarly supported in open ended slots q^7 in depending brackets Q^3 of the carriage. The slots Q^7 are intentionally made deep enough to allow the weight of the roll U to rest upon the roll 95 T and the belt T^6 is designed to be of such length that the lower roll X will be practically suspended thereby and will thus act as a belt tightener. The idle roll T^7 may also be made adjustable in slots q^8 of the carriage 100 frame for the same purpose.

It will of course be obvious that the plan of operation thus described will necessitate the previous placing of the sheets of stamps between the upper and lower webs and the 105 winding of the whole upon the receiving roller V. It is contemplated that this action may be accomplished by rotating the receiving roll V after the stamps have been exhausted to wind the webs again upon it and by inserting the sheets of stamps in exact 110 succession between the webs as they are thus rewound. Provision is, therefore, made for the application of a crank to the shaft of the receiving roll at v^1 to enable the roll to be 115 readily rotated by hand. Inasmuch, however, as the near proximity of the plunger mechanism and other parts at the front of the machine might render it inconvenient to properly insert the stamps between the rolls 120 T and U where they emerge, provision is further made for supporting the roll U in the shape of bearing slots q^9 provided in the upper extremities of the brackets q^6 which support the roll V. By slipping off the belts T^6 125 said roll U may be readily lifted into the slots q^9 and the point of insertion of the stamps between the webs will then be transferred to the lower side of the roll V where ample space exists for their proper manipulation. 130

An oil silk or similar fabric to which the stamps will have no tendency to adhere is desirably used for the web and it is contemplated that the several sheets of stamps will be attached at their meeting edges by some slight connection, such as adhesive strips of paper. In order to prevent the roll V from turning too easily in its bearings and to keep the web taut between the roll V and the feed 5 rolls friction belts v^2 are shown as secured at their ends to the carriage frame and as passing over grooves v^3 in the ends of the roll V and thence down to sustain weights v^4 which hold them in tension.

15 The entire carriage may be removed at any time by simply unscrewing the nut t^0 which holds the shaft T^1 in the bracket T^2 , and then slipping said shaft endwise until it is free from the bracket and from the ratchet 20 arm T^4 which will remain supported in the bracket by its sleeve t . The shaft in this case will not extend entirely through the roll T but will terminate at a sufficient distance from the receiving box E to permit the necessary endwise movement of the shaft; the roll T being journaled independently of the shaft by means of a sleeve t' which surrounds the shaft and projects at its ends into the journal bearings of the carriage. To prevent wear 25 on the stud q^1 sufficient to produce undesirable lost motion and to insure the successful passage of the stud through the point of intersection of the helical grooves, said stud is provided with a pivotally secured elongated 30 follower q^{10} made of generally elliptical shape so as to readily follow the curves of the screw.

The operation of the machine as a whole will be generally understood from the foregoing description of the construction and operation of its several component parts. It 40 may be explained, however, that the travel of the presser arms which forward the envelops to the plunger and fixing rolls is herein shown as made such that exactly two movements of said presser arms are necessary to bring the envelop in proper position to receive the stamp, while a third movement will carry the envelop along far enough to be caught between the fixing rolls. The envelops will in this manner be advanced by an 45 intermittent movement which will allow each envelop to remain stationary in correct position opposite the plunger for a time sufficient to permit the application of the stamp 50 in the manner described. In the construction shown the gears B^1 and C are of such relative sizes as to rotate the crank C^1 twice to each revolution of the drive shaft. Two reciprocations of the plunger will also obviously occur during this time owing to the provision of the double arm B and as before explained the ratchet mechanism will cause two movements of the carriage actuating screw to each revolution of the drive shaft. 55

60 In other words, one complete reciprocation

of the carrier mechanism accompanies each complete reciprocation of the plunger and a feed impulse of the stamp carriage takes place at the same time, except at the reversing points of its movement where a feed impulse of the sheet advancing rollers takes the place of a feed movement of the carriage. Obviously the several movements must be adjusted so as to occur in exactly correct relative relation to each other as regards 70 time. To this end the various adjustments described are provided, together with the clutch mechanism operated by the handle b^7 which enables the plunger and carriage mechanisms to be timed with relation to the 75 carrier mechanism, or to be thrown out of operation entirely while the carrier mechanism continues to run. The particular object of the latter function is to prevent the wasting of stamps by the continued action of the 80 plunger and stamp feed after the last envelop has passed, or by their action before the carrier mechanism has had time to present the first envelop to the plunger. In practice in starting the carrier mechanism 85 may be first operated to bring an envelop properly before the plunger, and the clutch then thrown in to set the plunger in operation at the proper moment.

It will be understood that a generic feature 90 of the present invention consists in the provision of a combined sealing and stamping machine for envelops, in which the sealing and stamping are accomplished by moving the envelops in succession through a unitary organization of moistening, sealing and stamping devices, such as will accomplish both desired results by what is in effect a single operation. And in so far as this generic feature is concerned, it is immaterial 95 whether the two functions of moving the envelops and of pressing their flaps against their bodies to seal them, is accomplished by separate mechanical means or not, provided that the complete machine, regardless of the 100 number or specific character of its constituent mechanisms or parts, is such as to accomplish both functions in the course of the same general operation and with the same 105 ultimate result of delivering the envelops, 110 properly stamped and sealed, at the end of their path of movement and as such general operation is completed.

It will furthermore be understood that 115 while particularly described and in this instance designed for the application of postage stamps to mail matter, a machine of generally similar construction and involving the same principles of operation but proportioned and arranged for the application of 120 labels of various shapes and sizes to any sort of printed or other matter capable of passing through the machine, may readily be devised, the plunger and die plate being made 125 of proper size and shape corresponding to the 130

stamp or label to be affixed. And in case the label or stamp or the envelop flap is not already gummed the moistening devices, or their equivalents, may be used to supply 5 mucilage to secure the necessary adhesion. It will also be understood that while the construction set forth is as a whole believed to be practically convenient and successful for the purposes intended, its several mechanisms 10 may be employed singly or together in connection with various other mechanisms to produce operative machines for the same or analogous purposes, and the invention is therefore intended to cover the valuable features 15 of the mechanisms considered separately as well as the complete combination shown. Obviously also the machine set forth may be employed for sealing stamped envelopes or envelops to which the stamps are affixed by a separate operation, or which do not require to be stamped, or it may be used for stamping envelops which are already sealed, or mail matter which does not require sealing, and finally it will be understood that 20 the various details of construction may be widely varied without in any way departing from the broad spirit of the invention.

We claim as our invention:-

1. The combination with a stamp affixing 30 mechanism and with means for feeding matter to be stamped to the affixing mechanism to receive the stamp, of a stamp carriage, means for moving the carriage past the affixing mechanism step by step and for returning 35 it step by step, means for advancing the stamps at each end of the carriage movement, and for supplying succeeding sheets to be in turn advanced on the carriage row by 40 row to the affixing mechanism as each preceding sheet is exhausted.

2. The combination with a stamp affixing mechanism including a plunger and opposing platen between which the matter to be stamped is introduced, of a stamp carriage, 45 means for moving the carriage past the plunger step by step with each reciprocation of the plunger and for returning it by similar reverse steps, means for advancing the stamps at each end of the carriage movement, and for supplying succeeding sheets of 50 stamps to be in turn advanced on the carriage row by row to the affixing mechanism as each preceding sheet is exhausted.

3. The combination with a stamp affixing 55 mechanism including a plunger and opposing platen, of a carrier for moving matter piece by piece between the plunger and platen with each reciprocation of the plunger, a stamp carriage, means for moving the carriage past 60 the plunger step by step with each reciprocation of the plunger and for returning it by similar reverse steps, means for advancing the stamps at each end of the carriage movement, and for supplying succeeding sheets of 65 stamps to be in turn advanced on the car-

riage row by row to the affixing mechanism as each preceding sheet is exhausted.

4. The combination with a stamp affixing mechanism, of means for moving matter to be stamped into stationary position before the affixing mechanism and for removing it therefrom by a succeeding movement, a stamp carriage, means for moving the carriage past the affixing mechanism step by step and for returning it step by step, 70 means for advancing the stamps at each end of the carriage movement, and for supplying succeeding sheets of stamps to be in turn advanced on the carriage row by row to the affixing mechanism as each preceding sheet is exhausted.

5. The combination with a stamp affixing mechanism including a plunger and opposing platen, of a carrier for moving matter to be stamped piece by piece between the plunger 85 and platen with each reciprocation of the plunger and for removing each piece with the succeeding reciprocation, a stamp carriage, means for moving the carriage past the plunger step by step with each reciprocation of 90 the plunger and for returning it by similar reverse steps, means for advancing the stamps at each end of the carriage movement, and for supplying succeeding sheets of stamps to be in turn advanced on the carriage 95 row by row to the affixing mechanism as each preceding sheet is exhausted.

6. The combination with a stamp affixing mechanism and with means for feeding matter to be stamped to the affixing mechanism, 100 of a stamp carriage, means for moving the carriage past the affixing mechanism step by step and for returning it step by step with a dwell of one interval at each end of its path of movement, means for advancing the stamps at each end of the carriage movement, and for supplying succeeding sheets of stamps to be in turn advanced on the carriage 105 row by row to the affixing mechanism as each preceding sheet is exhausted.

7. The combination with a stamp affixing mechanism, of means for moving the matter to be stamped into stationary position before the affixing mechanism and for removing it therefrom by a succeeding movement, a stamp carriage, means for moving the carriage past the affixing mechanism step by step with a dwell of one interval at each end of its path of movement, means for advancing the stamps at each end of said path of 115 movement, and for supplying succeeding sheets of stamps to be in turn advanced on the carriage row by row to the affixing mechanism as each preceding sheet is exhausted.

8. The combination with a stamp affixing 120 mechanism, of a receiving table for the envelops to be stamped, means for moving the envelops from the receiving table to the affixing mechanism, means located between the table and affixing mechanism by which 125

the envelops are moistened in said movement, and means for pressing the flaps against the envelops to seal them.

9. The combination with a stamp affixing mechanism, of means for moving matter to be stamped into stationary position before the affixing mechanism and for removing it therefrom by a succeeding movement, means for moistening the surface to be stamped during its passage to the affixing mechanism, a stamp carriage, means for moving the carriage past the affixing mechanism step by step and for returning it step by step, means for advancing the stamps at each end of the carriage movement, and for supplying succeeding sheets of stamps to be in turn advanced on the carriage row by row to the affixing mechanism as each preceding sheet is exhausted.
10. The combination with the stamp affixing mechanism and with means for feeding matter to the affixing mechanism to receive the stamps, of a stamp carriage, means for moving the carriage past the affixing mechanism step by step and for returning it step by step, a pair of flexible webs wound upon a supply roller journaled on the carriage and adapted to receive consecutive sheets of stamps between them, separate receiving rolls for the webs also journaled on the carriage, and means for rotating the rolls to advance the sheets of stamps at each end of the carriage movement.

11. The combination with the mechanism for detaching and applying the individual stamps, of a stamp carriage provided with a pair of flexible webs with the sheets of stamps between them, a feed roller over which said webs are carried, a receiving roller for one of the webs resting upon the feed roller and supported thereon by slots which engage its journals, a separate receiving roller for the other web also with its journals in slotted supports, flexible belting hanging from the upper receiving roll and suspending the lower receiving roll, and passing in contact with the feed roll, means for moving the carriage, and for moving the feed roll on the carriage when it reaches the extremity of its movement.

12. The combination with the stamp applying mechanism, of a passage way for conducting matter to be stamped to said mechanism, a carrier movable longitudinally of said passage, means for reciprocating said carrier past said mechanism by strokes shorter than the length of the carrier, and means for moving said carrier into said passage at the beginning of each forwarding stroke and for withdrawing it from the passage at the beginning of each return stroke.

13. The combination with the stamp applying mechanism, of a passage way for conducting matter to be stamped to said mechanism, a carrier comprising oscillating presser arms mounted on an axis extending longitudi-

dinally along said passage, means for reciprocating said arms longitudinally of said axis, and means for swinging the free ends of the arms into said passage at the beginning of each forwarding stroke and for withdrawing them therefrom at the beginning of each return stroke.

14. The combination with the stamp applying mechanism, of a passage way for conducting matter to be stamped to said mechanism, a carrier mechanism movable longitudinally of said passage, means for reciprocating said carrier longitudinally of said passage, means for moving the carrier into the passage at the beginning of each forwarding stroke and for withdrawing it therefrom at the beginning of each return stroke, and rubber pads on the carrier for frictionally engaging the matter to be stamped.

15. The combination with the stamp applying mechanisms, of a carrier mechanism comprising a reciprocatory bar, a stationary guide bar arranged parallel thereto, a slotted plate connected with the reciprocatory bar and engaging the guide bar, an actuating crank having a wrist pin engaging said slot, presser arms secured to the reciprocatory bar, and means for oscillating the presser arms with each reciprocation.

16. The combination with the stamp applying mechanisms, of a carrier mechanism comprising reciprocatory parts, oscillatory presser arms secured to said parts and rigidly connected together, a toggle inserted between a presser arm and a non-oscillating reciprocatory part, and means for operating the toggle at each end of the reciprocating movement to throw the ends of the presser arms alternately into and out of the path of movement of the matter to be stamped.

17. The combination with the stamp applying mechanisms, of a carrier mechanism comprising reciprocatory parts, oscillatory presser arms secured to said parts, a toggle inserted between a presser arm and a non-oscillating reciprocatory part, a tripping bar connected with said toggle and passing loosely through a stationary part, and stops on said tripping bar for throwing the toggle and oscillating the presser arms at each end of the reciprocating movement.

18. The combination with the stamp applying mechanism, and with a receiving table for the matter to be stamped, of a passage leading from the table to said mechanism, a carrier reciprocating along said passage past the table and stamp applying mechanism, means for moving said carrier into said passage at the beginning of each forwarding stroke and for withdrawing it at the beginning of each return stroke, and means for pressing the matter on the table towards the carrier.

19. The combination with a stamp affixing mechanism connected by a passage with a

receiving table for the matter to be stamped, of a carrier reciprocating along said passage, means for moving said carrier into said passage and laterally against the face of the matter to be stamped at the beginning of each forwarding stroke and for withdrawing it at the beginning of each return stroke, a pad on the carrier for frictionally engaging the matter to be stamped, and means for pressing 10 said matter toward the carrier.

20. The combination with the stamp applying mechanism, and with a receiving table for the matter to be stamped, of a connecting passage, a carrier comprising oscillating presser arms mounted on an axis extending along said passage, means for reciprocating said arms longitudinally of said axis, and means for swinging the free ends of the arms into said passage at the beginning of each 15 forwarding stroke and for withdrawing them at the beginning of each return stroke, and means for pressing the matter on the table toward the carrier.

21. The combination with a stamp affixing mechanism including a plunger and opposing platen, of a stamp carriage, means for moving the carriage past the plunger step by step and for returning it step by step with a dwell of one interval at each end of its path of 30 movement, and means for advancing the sheet of stamps on the carriage at each end of its path of movement, a receiving table for the matter to be stamped, a passage leading from said table to between the plunger 35 and platen, a reciprocating carrier movable longitudinally of the passage, means for moving said carrier into said passage at the beginning of each forwarding stroke and for withdrawing it at the beginning of each return 40 stroke, and means for pressing the matter on the table toward the carrier.

22. The combination with the stamp applying mechanisms, of a carrier mechanism comprising reciprocating presser arms and means for moving said arms alternately into 45 and away from the path of the matter to be stamped, a moistening device held yieldingly in the path of said matter, and a cam surface on a presser arm adapted to engage and force 50 back the moistening device at intervals.

23. The combination with a stamp affixing mechanism including a plunger and platen, of a stamp carriage, means for moving the carriage past the plunger step by step with each 55 reciprocation of the plunger and for returning it by similar reverse steps, means for advancing the sheet of stamps on the carriage at each end of its path of movement, a receiving table for the envelopes to be stamped, 60 means for moving said envelopes in succession from the receiving table past the plunger, means located between the table and plunger by which the envelop flaps are moistened in this movement, and means for pressing the 65 flaps against the envelopes to seal the latter.

24. The combination with a stamp affixing mechanism including a plunger and platen and means for feeding stamps between the die and platen, of a receiving table for the envelopes to be stamped, a reciprocating carrier 70 extending from the table past the plunger, means for pressing the envelopes on the table toward the carrier, means for moving said carrier against the envelopes at the beginning of each forwarding stroke and away from the 75 envelopes at the beginning of each return stroke, means located between the table and plunger by which the flap of each envelop is moistened in its movement by the carrier and presser devices for sealing the flap 80 against the envelop.

25. The combination with a stamp affixing mechanism, of a receiving table for the envelopes to be stamped, means for moving the envelopes in succession from the receiving table to the affixing mechanism, means located 85 between the table and affixing mechanism by which the envelop flaps are moistened in said movement, and means for pressing the flaps against the envelopes to seal them. 90

26. The combination with a stamp affixing mechanism and with an automatic stamp feed capable of feeding several sheets of stamps in continuation to the affixing mechanism, of an automatic envelop feed capable 95 of feeding envelopes singly to the affixing mechanism, and means for moistening and sealing the flaps of said envelopes during the feeding operation.

27. The combination with a stamp affixing mechanism, of means for holding several sheets each made up of a plurality of individual stamps, and feed mechanism for advancing the several sheets in continuation of each other and for presenting each individual 100 stamp of each and every sheet to the affixing mechanism in continuous succession. 105

28. The combination with a stamp affixing mechanism, of a receiving table for the envelopes to be stamped, means for moving the 110 envelopes from the receiving table to the affixing mechanism, means located between the table and affixing mechanism by which the envelop flaps are moistened in said movement, and means for pressing the flaps 115 against the envelopes to seal them.

29. In a combined sealing and stamping machine for envelopes, the combination with a stamp affixing mechanism to which the envelopes are moved in succession, of means 120 located along their path of movement for moistening the flaps and stamp receiving faces of the envelopes, and mechanical elements operating to move the envelopes past the moistening means to the affixing mechanism and press the flaps against the bodies of the envelopes to seal them. 125

30. In a combined sealing and stamping machine for envelopes, the combination with a stamp affixing mechanism, of a receiving ta- 130

ble for the envelops to be stamped, means for moistening the envelops located between the receiving table and affixing mechanism, and mechanical elements operating to move the envelops from the receiving table to the affixing mechanism and press the flaps against the bodies of the envelops to seal them.

31. The combination with a stamp affixing mechanism, of a carrier mechanism comprising a reciprocating presser arm, and means for moving said presser arm alternately into and away from the path of the matter to be stamped, a moistening device normally held in the path of the matter and arranged for moistening contact therewith as the matter is carried past it, and means on the presser arm for engaging and forcing back the moistening device at intervals and so as to prevent unnecessary moistening of the matter.

32. In a combined sealing and stamping machine for envelops, the combination with a stamp affixing mechanism to which the envelops are movable in succession, of means for moistening the envelops located along their path of movement, and means for moving the envelops past the moistening means and affixing mechanism and pressing the flaps against the bodies of the envelops to seal them.

33. In a combined sealing and stamping machine for envelops, the combination with a stamp affixing mechanism to which the envelops are movable in succession, of means for moistening the envelops located along their path of movement, means for moving the envelops past the moistening means and affixing mechanism and turning down the flaps against the bodies of the envelops, including means beyond the stamp affixing mechanism for applying pressure tending to insure the sealing and stamping.

34. In a combined sealing and stamping machine for envelops, the combination with a stamp affixing mechanism to which the envelops are movable in succession, of means for sealing the flaps of the envelops located along their path of movement and including means for moving said envelops past the moistening means to and beyond the affixing mechanism.

35. In a combined sealing and stamping machine for envelops, the combination of a stamp affixing mechanism to which the envelops are movable in succession, of means for sealing the flaps of the envelops located along their path of movement including means for moving said envelops past the moistening means to the affixing mechanism and means beyond the affixing mechanism for advancing the envelops and applying final pressure thereto.

36. In a combined sealing and stamping machine for envelops, the combination with a stamp affixing mechanism to which the envelops are movable in succession, of means for

moistening the envelops, means for moving the envelops past the moistening means and affixing mechanism and turning down the flaps against the bodies of the envelops, and a pair of rolls beyond the affixing mechanism for subjecting the envelops to final pressure.

37. In a combined sealing and stamping machine for envelops, the combination with a stamp affixing mechanism to which the envelops are movable in succession, of means located along their path of movement for moistening the flaps and stamp receiving faces of the envelops during their movement, and mechanical elements operating to move the envelops past the moistening means and affixing mechanism and to press the flaps against the bodies of the envelops to seal them and to cause a dwell of each envelop opposite the affixing mechanism.

38. In a combined sealing and stamping machine for envelops, the combination with a stamp affixing mechanism, of a receiving table for the envelops to be stamped, means for moistening the envelops during the movement thereof, said means being located between the receiving table and affixing mechanism, and means for moving the envelops from the receiving table to and beyond the affixing mechanism and to press the flaps against the bodies of the envelops to seal them, said means also producing a dwell of the envelop opposite the affixing mechanism.

39. In a combined sealing and stamping machine for envelops, the combination with a stamp affixing mechanism, of a receiving table for the envelops to be stamped, devices located between the receiving table and affixing mechanism for moistening the flaps and stamp receiving faces of the envelops, and moving and pressing means for moving the envelops from the receiving table past the affixing mechanism and closing the flaps against the bodies of the envelops to seal them.

40. A machine for stamping and sealing envelops comprising a table for receiving the envelops, means for moving the envelops along a fixed path of movement intermittently and with a period of rest or dwell, means for moistening the envelops for sealing, means for closing down the flaps against the bodies of the envelops to seal them, means for moistening the stamp receiving faces of the envelops, and means for affixing stamps to the moistened faces of the envelops during said period of rest or dwell.

41. A machine for sealing and stamping envelops comprising a magazine or table for holding the stack or pile of envelops, means for moving the envelops from the stack or pile intermittently and with periods of rest or dwell, means for moistening the envelops for sealing, means for closing the flaps against the bodies of the envelops to seal them, means for moistening the stamp receiving

faces of the envelops, and means for affixing stamps to moistened faces of the envelops during the periods of rest or dwell.

42. A machine for stamping and sealing envelops comprising a magazine or table for holding a stack or pile of envelops, means for moving the envelops successively and by an intermittent motion from this stack or pile, with periods of rest or dwell, means for moistening the envelops for sealing and for turning down the flaps against the bodies of the envelops, means for moistening the stamp receiving faces of the envelops, and means for affixing the stamps to the moistened faces of the envelops during the periods of rest or dwell.

43. A machine for stamping and sealing envelops comprising a magazine or table for holding a stack or pile of envelops, means for moving the envelops one at a time from the stack or pile by an intermittent movement allowing each envelop a period of rest or dwell, means for moistening the envelops in succession for sealing and for closing the flaps against the bodies of the envelops, means for moistening the stamp receiving faces of the envelops in succession, and means for affixing a stamp to the moistened face of each successive envelop during its period of rest or dwell.

44. A machine for stamping and sealing envelops comprising a magazine or table for holding a stack or pile of envelops, means for moistening the stamp receiving faces of the envelops, a stamp affixing mechanism, means for moistening the flaps of the envelops and for closing the flaps against the bodies of the envelops and means for moving the envelops in succession from the magazine to and beyond the affixing mechanism with a period of rest or dwell at the affixing mechanism during which a stamp is affixed to each envelop in turn.

45. A machine for stamping and sealing envelops comprising a table for receiving the envelops, means for moistening the stamp receiving faces of the envelops, means for moistening the envelops for sealing and for closing the flaps against the bodies of the envelops, and means for moving the envelops from the table in a substantially horizontal path to and beyond the affixing mechanism with a period of rest or dwell at the affixing mechanism during which period a stamp is affixed to the moistened face of each envelop in turn.

46. A machine for stamping and sealing

envelops comprising a magazine or table for holding a stack or pile of envelops, means for moistening the stamp receiving faces of the envelops, a stamp affixing mechanism, means for moistening the envelops for sealing and for closing the flaps against the bodies of the envelops, and means for moving the envelops in succession from the stack or pile in a substantially horizontal path to and beyond the affixing mechanism with a period of rest or dwell at the affixing mechanism during which period a stamp is affixed to the moistened face of each envelop in turn.

47. The combination with a stamp affixing mechanism and with an automatic stamp feed capable of feeding two or more sheets of stamps in continuation to the affixing mechanism, of an automatic envelop feed capable of feeding envelops to the affixing mechanism.

48. The combination with a stamp affixing mechanism, of means for holding two or more sheets each made up of a plurality of individual stamps and feed mechanism for advancing the sheets in continuation of each other and for presenting the stamps to the affixing mechanism in continuous succession.

49. The combination with a stamp affixing mechanism, of means for holding several sheets each made up of a plurality of individual stamps and feed mechanism for advancing the several sheets in continuation of each other and presenting the stamps to the affixing mechanism in continuous succession, and an automatic envelop feed delivering envelops in continuous succession to the affixing mechanism.

50. The combination of a magazine or carrier for containing a stack of envelops, a feeder operable to discharge envelops successively from the stack, means for moving envelops in a predetermined path subsequent to the operation of the feeder thereon, suitable sealing means, a flap moistener situated between the feeder and the sealing devices, and means for affixing stamps to the envelops prior to the action of the sealing devices thereon.

In testimony that we claim the foregoing as our invention we affix our signatures in presence of two subscribing witnesses this 22d day of September, A. D. 1897.
